(57) **CLAIM**

The ornamental design for a handheld radio control head, as shown and described.

DESCRIPTION

FIG. 1 is a perspective view of the handheld radio control head;

FIG. 2 is a front elevational view thereof;

FIG. 3 is a rear elevational view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken line showing of environmental structures is for illustrative purposes only and forms no part of the claimed design.
